Primary Examiner — Barbara Fox*Assistant Examiner* — Messina L Smith(74) *Attorney, Agent, or Firm* — Adler Pollock & Sheehan P.C.; Daniel J. Holmander, Esq.(57) **CLAIM**

The ornamental design for a mesh cooking basket, as shown and described.

DESCRIPTION

FIG. 1 is a perspective view of a mesh cooking basket, showing the new design;

FIG. 2 is a front view thereof;

FIG. 3 is a rear view thereof;

FIG. 4 is a left side view thereof;

FIG. 5 is a top view thereof; and,

FIG. 6 is a bottom view thereof.

The broken lines in the drawings depict portions of the mesh cooking basket that form no part of the claimed design.
